UNITED STATES PATENT OFFICE.

SHELLEY B. HUTCHINSON, OF YPSILANTI, MICHIGAN.

NEWSPAPER OR PERIODICAL.

SPECIFICATION forming part of Letters Patent No. 758,139, dated April 26, 1904.

Application filed December 22, 1903. Serial No. 186,217. (No model.)

To all whom it may concern:

Be it known that I, SHELLEY B. HUTCHINSON, a citizen of the United States, residing at Ypsilanti, in the county of Washtenaw and State of Michigan, have invented certain new and useful Improvements in Newspapers or Periodicals, of which the following is a specification, reference being had therein to the accompanying drawings.

10 The invention consists in new and useful improvements in newspapers, and relates to the construction of a flap or corner on the paper comprising a series of triangular portions folded over onto the outside of the paper and 15 perforated at the fold, so that one or more may be readily detached and so that in case only one is detached the next one below will be exposed to view, the flaps being printed with any desired matter, either advertising or 20 coupons, all as more fully hereinafter described, and particularly pointed out in the claims.

In the drawings, Figure 1 is a front elevation showing a newspaper with four flaps at the corner, the flaps being slightly turned up, so as 25 to be shown in perspective. Fig. 2 is a front elevation of one of the leaves of the paper, illustrating the flap turned back to illustrate the line of perforation; and Fig. 3 is a front 30 elevation showing the flaps turned down flat on the front.

At the present time it is quite general for newspapers in some or all of their editions to have guessing-contests or puzzles, puzzle-pictures, or coupons printed into the paper, which 35 it is necessary for the subscriber to cut out and return to the paper, with answers to the puzzles or rebus, or to return the coupon for some purpose, and these coupons are printed, ordinarily, in the body of the page, and 40 in order to get them out they have to be cut. These coupons thus applied are not applied in such a distinctive manner as to attract attention to them, nor are they readily removable

without destroying some other matter on the 45 paper.

My invention consists in applying to one corner a series of coupons formed by perforating the paper in a diagonal line, as shown at A, Fig. 2, and then folding that portion of 50 the paper beyond the perforations, being a triangular flap B, down upon the outside of the paper, one flap being superposed upon another, which always brings such coupons directly to the attention of the purchaser and 55 makes the same readily detachable without destroying any of the valuable reading-matter on the paper.

I preferably print upon the outer face C of the flap, so that when the flap is folded down 60 the printed matter will be on the outside, and in case one flap is removed the printed matter on the one below it will still be outside, and in this manner all the flaps can be successively 65 brought into view without opening the paper.

I may further direct attention to the flaps or coupons by printing them in different colors from that of the remainder of the paper or periodical, so that a person purchasing the paper will have his attention immediately 70 called by the color scheme to these particular coupons, which makes it very desirable for advertising, bringing the same prominently to the attention of whoever may see that particular paper or periodical.

75 What I claim as my invention is—

1. A newspaper having a series of diagonal perforations across the corner of superposed leaves forming flaps or coupons of the corners, said flaps or coupons being turned down on 80 the outside of the paper, whereby each may be separately removed without disturbing those beneath.

2. In a newspaper a series of superposed leaves or sheets each having a diagonal perforation across the same corner forming flaps or coupons, the flaps or coupons being folded over the front face of the paper, the flap or 85

coupon on the inner leaf or sheet being on the outside and having printed matter upon the exposed or outer faces thereof.

3. A newspaper composing a series of superposed sheets each having a diagonal perforation across the same corner forming flaps or coupons, said flaps or coupons being turned down the flap on the inner leaf being turned over those upon the leaves in front, and hav-

ing printing thereon of different color from the remainder of the printing of the paper substantially as and for the purpose described.

In testimony whereof I affix my signature in presence of two witnesses.

SHELLEY B. HUTCHINSON.
